UNITED STATES PATENT OFFICE.

ROBERT E. WRIGHT, OF LINCOLN, NEBRASKA.

ATTACHMENT FOR CYLINDER PRINTING PRESSES.

Application filed November 21, 1921. Serial No. 516,796.

To all whom it may concern:

Be it known that I, ROBERT E. WRIGHT, residing at Lincoln, in the county of Lancaster, State of Nebraska, have invented 5 certain new and useful Improvements in Attachments for Cylinder Printing Presses; and I do hereby declare the following to be a full, clear, and exact description of the invention, such as will enable others skilled 10 in the art to which it appertains to make and use the same.

This invention relates to an attachment for a printing press and involves the provision of a device of this character for imprinting 15 numbers, dates or other data supplementary to the main body of matter printed on sheets by the press itself.

Heretofore in printing sheets, for example, with consecutive numbers, the common practice has been to allow space in the printing form for the insertion of a typographical numbering machine. Machines of this character are provided with means for automatically advancing the number 25 type in consecutive order as the main body of matter is being printed so that the sheets, consisting of certificates, coupons and the like, will be consecutively numbered as they are printed. This method of printing sheets 30 with supplemental matter of the character indicated has various disadvantages. In the first place the correct positioning of the machine in the printing form requires that the most exact adjustments be made in order 35 not only that the numbers or other matter will be accurately placed on the sheet, but also that the type of the machine must be precisely type high to obtain the impression from the type of the machine without af- 40 fecting the printing of the type in the remainder of the printing form. Furthermore, since the end of the operating plunger of the numbering machine must project above the level of the type thereof to be ac- 45 tuated when the printing form is impressed upon the sheet, in consequence of which the end of the plunger is linked along with the type, various expedients must be resorted to to block out the plunger so that it will be 50 prevented from printing. Frequently it is desired to print identifying matter such as numbers in different colors from the main body of the printed matter; and a further obvious disadvantage, therefore, in placing 55 the numbering machine in the form is that it

can be made to print only in the same color as the rest of the type inasmuch as it takes ink from the same rollers that ink the type in the form.

The attachment constituting the present 60 invention is constructed and arranged for operation separate from the printing form although it is actuated, in the preferred form of construction, by connection with the operating parts of the press. Adjustments 65 to secure the correct spacing of the supplementary matter to be supplied by the attachment are simple and readily made, and the type of the attachment may be type high or more than type high. Moreover, the 70 printed matter to be supplied by the attachment may be in the same color or a color different from the rest of the printing since the attachment embodies means independent 75 of the inking rollers of the press for inking its type.

The attachment is adapted for use particu- 80 larly in conjunction with cylinder or drum types of presses, and consists of a rotary type holder which is constructed and ar- ranged for coaction with the impression cylinder of the press independently of the printing form but in cooperation therewith to supply imprints of matter supplemental 85 to the main body of matter contained in the printing form, and is preferably adjustable with relation to the impression cylinder so that the type in the holder may be readily moved for positioning on the sheet in accordance with the requirements of a specific 90 printing job. The type holder which, in the form of construction hereinafter described, consists of a reel mounted on a shaft and carrying a type holder in the form of an adjustable clamp, is preferably arranged for 95 retraction to inoperative position when it is desired to run the press without the attachment. The attachment includes means for driving the type holder in timed relation with the impression cylinder of the press 100 and accordingly also with the bed of the press carrying the printing forms. A convenient arrangement of driving connection is from the operating parts of the press, for example, by gear connection between the 105 shaft carrying the type holders and the cylinder gear of the press.

In one form of construction of the attachment means are embodied for inking the type thereof independently of the inking 110

rollers of the press and so if it is desired a different color ink may be used. Such inking means consist preferably of inking rollers carried by the attachment, one of the 5 rollers being a vibrator roller actuated by the corresponding roller of the press to secure proper distribution of the ink on the type of the attachment.

In the specific embodiment of the invention described hereinafter the operating parts of the attachment are mounted upon a swinging frame pivoted to a standard which is bolted on the frame of the press. By connection with the operating lever of 15 the press, the swinging frame may be advanced to printing position, or retracted to inoperative position when it is desired to run the press without the attachment. In this specific example of the attachment the 20 construction is adapted primarily for numbering work by means of a numbering machine held in the clamps carried on a reel constituting the rotary type holder. In order that the operating plunger of the numbering machine will be prevented from 25 printing, the inking roller of the attachment supplying ink to the type of the numbering machine is preferably a sectional form of roller, the sections composing which may be moved so that ink will be applied to the type only of the machine and not the plunger.

The invention is illustrated in the accompanying drawings in the form of a numbering attachment in application, as example, 25 to a cylinder press of the type known as the Babcock press, and in the drawings

Fig. 1 is a view in elevation of a portion of the printing press illustrating the numbering device attached thereto;

Fig. 2 is a sectional detail view of the cylinder of the press and the outer part of the attachment showing one of the numbering machines in operative position;

Fig. 3 is a view along the line 3-3 of 45 Fig. 1;

Fig. 4 illustrates one of the cylinders supporting the clamps for holding the numbering machines;

Fig. 5 is a sectional view taken through 50 the periphery of the reel and one of the clamps showing the numbering machine in position within the latter; and

Fig. 6 is a view of one of the liners employed for adjusting the numbering machine in position within the clamp;

Fig. 7 illustrates the sectional inking roller of the attachment.

Referring to the drawings in which like characters indicate corresponding parts 60 throughout the several views, the attachment constituting the invention is supported on a frame 7 which in turn is bolted as at 8 to the frame 9 of the press. Pivoted in bearings 10 is a frame 11 which carries the operating parts of the attachment. Bolted

to the frame 11 as at 12 are bearings 13 in which is journaled a shaft 14. Mounted on the shaft 14 is a plurality of reels 15 in the form of spoked wheels having hubs 16 fitting the shaft and provided with any suitable fastening means such as pins or screws 17 for securing the reels in adjusted position along the shaft. The periphery of each of the reels is formed with tapering sides 18 providing retaining guideways for 75 a plurality of clamps 19 slidably mounted upon each of the reels. The clamps 19 are made in two pieces having complementary tapering recesses fitting the tapering sides 18 of the periphery of the reel and forming a dovetail sliding connection. The two parts of the clamp 19 are held together by means of a bolt 20 and nuts 21 at each end thereof by which the parts of the clamp may be forced together to tighten the latter in adjusted position upon the reel. The upper part of each of the clamps 19 is cut away as at 22 to provide a recess for receiving the numbering machine which may be any of the known commercial numbering 90 machines in use. Numbering machines of various sizes are accommodated in the upper recess of the clamp by providing liners such as 23, illustrated in detail in Fig. 6, the liners being provided with pins 24 for fastening them in the apertured walls of the clamps forming the recess as illustrated in Fig. 5. The clamps and numbering machines therein, disposed around the periphery of each of the reels, and the number of 100 reels and their positions on the shaft 14 may be regulated to meet the requirements of 95 each specific printing job.

In view of the location of the numbering machine above the type line 25 of the reciprocating bed 26 of the press, means are provided for inking the type of the numbering machines independently of the inking rollers 27 of the press. Such means consist of a series of rollers 28, 29 and 30 journaled in bearings 31 bolted to the frame 11. The rollers are customarily three in number, the roller 28 taking ink from the ink receptacle being of metal, and the rollers 29 and 30 being of composition material and transferring the ink from the metal roller 28 to the type of the numbering machines. Like the intermediate vibrator roller of the system of rollers 27 inking the type of the printing form held in the reciprocating bed 26 of the press, the intermediate roller 29 of the attachment is arranged to be reciprocated back and forth across the rollers 28 and 30 to spread the ink and produce an even distribution thereof on the type of the numbering machines. The vibrator roller or intermediate roller 27a of the press is reciprocated laterally across the surfaces of the remaining rollers by means of an eccentric 32, the system of links 33 110 115 120 125 130

and the pin 34 riding in grooved wheel 35 at the end of the roller as is common in printing press construction. For the purpose of imparting a reciprocatory movement to the intermediate spreader roller 29 of the attachment, a link 36 is provided which is pivoted to the frame 7 as at 37. At one end of the link 36 is a pin 38 which rides in the grooved wheel 35 on one end of the intermediate roller 27^a. The opposite end of the link 36 has a pin 39 which rides in a corresponding grooved wheel 40^a at one end of the intermediate roller 29. As the vibrator roller 27^a of the press is reciprocated back and forth by means of the eccentric 32 and link connections, the reciprocatory movement of this roller is communicated to the roller 29 of the attachment thus effecting a lateral movement of this roller across the surfaces of the rollers 28 and 30, and producing an even distribution of the ink on the roller 30 and consequently on the face of the type of the numbering machines.

In the position of the attachment illustrated in Figs. 1 and 2, the swinging frame 11 is supported in a horizontal position in which position the type of the numbering machines will contact with the stock fed to the cylinder 40 of the press from the feeder 41. In order that the attachment may be retracted to inoperative position a link 42 is provided which is attached at one end thereof at 43 to the operating lever 44 of the press and pivoted at the other end thereof as at 45 to the frame 11. By operating the lever 44, therefore, the frame 11 and the parts of the attachment mounted thereon may be raised above the frame 7 and moved out of operative position.

The shaft 14 has at one end a gear 46 which is in mesh with the cylinder gear 47 of the press by which the shaft 14 is driven. The gearing is in the ratio of two revolutions of the shaft 14 to one revolution of the press cylinder when the attachment is used in conjunction with a press of the drum cylinder type, and in the ratio of one revolution of the shaft 14 to one of the press cylinder when the attachment is used on a type of press known as the two-revolution cylinder.

It will be seen by an inspection of Fig. 5 that the numbering machine consists of a plurality of reels 48 carrying number type, the first of which series of reels is operated by a plunger 49, the remaining reels being advanced as the numbers progress. In the absence of any means to prevent it the plunger would make an impression upon the stock being fed to the cylinder in the path of the numbering machines, and so the roller 30 is preferably of the type known as a sectional roller Fig. 7, that is one composed of one or more short sections so that the type

only of the numbering machine will be inked and in this way the impression of the plunger 49 on the stock is avoided.

The numbering of the stock by means of the attachment above described in operation independent of the printing of the main body of printing matter by the printing form makes it possible to employ numbering machines the type of which may be "type high" or more than "type high"; and, moreover, the color of ink employed for inking the type of the numbering machine may be the same or a different color from that used in the press proper.

The operation of the attachment will be evident from the description already given. The paper stock is fed to the cylinder 40 from the feed table 41 and passes along the surface of the cylinder where it comes in contact with the numbering machines previously adjusted in position to impress numbers, dates or other data supplemental to the main body of printed matter which is subsequently impressed on the stock by the printing form contained in the bed 26 of the press.

I claim:

1. The combination with a drum cylinder type press, including an impression cylinder and a printing form, of a numbering attachment including a frame, a shaft mounted in said frame and carrying a reel, and an adjustable clamp on said reel for holding the numbering machine, the latter having a plunger for advancing the numbers, said frame being pivotally mounted and provided with means for bringing the numbering machine into operative engagement with the impression cylinder, and said reel being approximately one-half the diameter of the impression cylinder, and a sectional roller for inking the type only of the numbering machine to prevent an impression of the actuating plunger thereof, substantially as described.

2. The combination with a cylinder press having a set of inking rollers including a vibrator roller of an attachment including a frame, a shaft mounted in said frame and carrying a reel, and a type holder on said reel, said shaft being positioned relative to the impression cylinder to bring the type in said holder in contact with the stock to be printed, a set of rollers including a vibrator roller for supplying ink to the type in said holder, means operated by the vibrator roller of the press for actuating the vibrator roller of the attachment, and a driving connection for actuating the said shaft to move said reel in timed relation with the impression cylinder.

3. The combination with a cylinder press of a numbering attachment including a frame, a shaft mounted in said frame and carrying a reel, and an adjustable clamp

4
on said reel for holding a numbering machine, the latter having a plunger for advancing the numbers, said shaft being positioned relative to the impression cylinder to bring the type of the numbering machine in contact with the stock to be printed, a set of rollers for supplying ink to the numbering machine including an adjustable sectional roller for inking the type only of the 10 numbering machine to prevent an impression of the actuating plunger thereof and a driving connection for actuating the said shaft to move the said reel in timed relation with the impression cylinder.
15 4. The combination with a cylinder press of a numbering attachment including a frame, a shaft mounted in said frame and carrying a reel, and a circumferentially adjustable clamp on said reel for holding a 20 numbering machine means for adjusting said numbering machine within said clamp circumferentially and radially with respect to said reel, said shaft being positioned relative to the impression cylinder to bring 25 the type of the numbering machine in con-

tact with the stock to be printed, and means independent of the inking rollers of the press for supplying ink to the type in said holder and a driving connection for actuating the said shaft to move the said reel 30 in timed relation with the impression cylinder.

5. The combination with a cylinder press of a numbering attachment including a pivotally mounted frame, a shaft mounted in 35 said frame adjacent to the impression cylinder of the press, a plurality of reels adjustably mounted on said shaft each having thereon a clamp for holding a numbering machine, a set of rollers for supplying ink 40 to the type of the numbering machines, a lever for swinging the frame to bring the numbering machine into and out of printing position relative to the press cylinder, and a gear connection for driving said shaft 45 to move said reels in timed relation with the press cylinder.

In testimony whereof I affix my signature.

ROBERT E. WRIGHT.
